UNITED STATES PATENT OFFICE.

JOHN FLANAGAN, OF DAVENPORT, IOWA.

LIFTING-JACK.

1,329,116.

Specification of Letters Patent. Patented Jan. 27, 1920.

Application filed June 9, 1919. Serial No. 302,814.

To all whom it may concern:

Be it known that I, JOHN FLANAGAN, a citizen of the United States, residing at Davenport, in the county of Scott and State 5 of Iowa, have invented certain new and useful Improvements in Lifting-Jacks, of which the following is a specification.

This invention relates to lifting jacks.

One of the objects of this invention re- 10 sides in the provision of a lifting jack which is manually manipulated.

Another object of this invention resides in the provision of a lifting jack consisting of an embodiment of coacting elements 15 whereby the leverage of the lifting lever can be varied according to the weight to be lifted.

A still further object of this invention resides in the provision of a lifting jack having means whereby the lifting lever can 20 be locked to support the weight in elevated position.

With these and other objects in view, this invention resides in certain novel features 25 of construction and arrangement of elements to be more particularly set forth in the specification herewith and pointed out in the appended claim, it being understood that the right is reserved to resort to such 30 changes in construction as come within the scope of the claim.

In the accompanying drawing:—

Figure 1 is a side view of a lifting jack as constructed in accordance with this in- 35 vention showing the lifting lever in ele- vated position by dotted lines;

Fig. 2 is a view thereof taken at right angles thereto with the lifting lever re- moved.

40 In the present embodiment of this inven- tion, the numeral 5 designates a U-shaped hanger having the terminals 6 of its arms 7 secured together by a rivet 8 and held in spaced relation by a sleeve 9.

45 Loosely secured to the medial portion 10

of the hanger 5 is a hook 11 by which the hanger is suspended in operative position from a stationary object, not shown.

Pivotedly supported by a bolt 12 which is passed through sets of alining apertures 13 50 in the arms 7 of the hanger is a lifting lever 14.

The aforesaid lifting lever 14 is of any suitable length and is provided with a multiplicity of apertures 15 whereby the same 55 can be shifted in various positions so that the leverage on opposite sides of the bolt 12 can be altered to suit the weight to be lifted.

The forward end of the lever 14 is pro- 60 vided with a flexible element 16 herein shown in the form of a chain. In order to adjustably support the chain at the forward end of the lever, a U-shaped bolt 17 is fas- tened to the lever so that any particular 65 link of the chain can be retained in locked position thereto.

Carried by the rivet 8 on the sleeve 9 is a flexible element 18 in the form of a hook 19 and ring 20. This flexible element is 70 adapted to hold the handle in depressed po- sition after the weight of the object to be lifted has been elevated.

With this invention fully set forth, it is manifest that a lifting jack is provided 75 which is cheap to manufacture, readily oper- able, and convenient to transport.

Having thus described this invention, what I claim is:—

An article of the character described, the 80 combination of a U-shaped hanger, a lever pivotally secured thereto, a hook loosely supporting said hanger, a flexible element carried by said lever, a rivet securing the free ends of the hanger together, a sleeve 85 on said rivet, a ring on the sleeve, and a hook on said ring.

In testimony whereof I affix my signature.

JOHN FLANAGAN.
